UNITED STATES PATENT OFFICE.

LOUIS P. DAGES, OF BALTIMORE, MARYLAND, ASSIGNOR OF ONE-HALF TO LEONEL F. REVELL, OF BALTIMORE, MARYLAND.

LOCK.

1,417,038.

Specification of Letters Patent. Patented May 23, 1922.

Application filed October 22, 1921. Serial No. 509,597.

To all whom it may concern:

Be it known that I, LOUIS P. DAGES, a citizen of the United States, residing at Baltimore city, State of Maryland, have 5 invented certain new and useful Improvements in Locks, of which the following is a specification.

This invention relates to permutation locks employing rotatable tumblers, and its 10 object is to provide a very simple and efficient lock of this kind embodying certain novel and improved features of construction and modes of operation as will be described in detail hereinafter.

15 In order that the invention may be better understood, reference is had to the accompanying drawings, forming a part of this specification, and in said drawings:

Figure 1 is a face view of the lock; Fig. 20 2 is a longitudinal section on the line 2—2 of Fig. 1; Fig. 3 is an elevation showing one side of the lock, a face plate being removed; Fig. 4 is an elevation, partly in section, showing the other side of the lock; 25 Fig. 5 is a vertical section on the line 5—5 of Fig. 1; Fig. 6 is a sectional detail on the line 6—6 of Fig. 2, and Fig. 7 is a sectional detail on the line 7—7 of Fig. 2.

Referring specifically to the drawings, 10 0 denotes a door or other closure in which is set, flush with one side thereof, a casing 11 enclosing the lock which is the subject matter of the present application for patent.

The front of the casing is closed by an es- 35 cutcheon or face plate 12. The outer end of the casing is open and set flush with the edge of the door, and from said end is adapted to be projected the bolt 13 for locking the door in closed position. This bolt 40 is a sliding one and it is controlled by certain rotatable permutation tumblers to be presently described.

In the bolt 13 is a longitudinal slot 14 in which seats a block 15 on which the bolt is 45 slidable, said block having its edges grooved, as shown at 15^a in Fig. 5 to receive ribs 14^a on the corresponding edges of the slot. The block is made in two sections, as clearly shown in Figs. 2 and 5, so that it may be 50 assembled in the bolt slot.

From one side of the block 15, perpendicular thereto, extends a stem 16. This stem passes through the two sections of the block and has on one side of the block a 55 nut 16^a and on the other side a shoulder 16^b,

whereby the block sections are fastened together, they being clamped between the nut and the shoulder, as clearly shown in Fig. 2.

On the projecting end of the stem 16 is rotatably mounted a sleeve 17 carrying at 60 its inner end a rotatable tumbler in the form of a cross bar 18 projecting radially from the sleeve. On the sleeve 17 is rotatably mounted a second sleeve 19 carrying a tumbler 20 similar to the tumbler 18. The two 65 tumblers are contiguous and they are rotatable about an axis common to both.

In the lock casing 11, over the tumblers 18 and 20, is rigidly mounted a plate 21 provided with a circular opening 22 in which 70 the tumblers seat and are free to rotate. From the opening 22 a slot 23 leads rearwardly, the same running in the direction of the length of the bolt 13. One end of each tumbler is of a width to pass into the 75 slot 23, and the tumblers at their other ends are wider than the slot. Upon turning the tumblers to bring their narrow ends in registering position, and also turning the same to come into alignment with the slot 23, the 80 bolt 13 may be retracted, the tumblers moving rearwardly into the slot. When the bolt is in advanced position and the tumblers are set cross-wise of the slot 23 as shown in Fig. 3, the bolt is locked.

85 The stem 16 is used for advancing and retracting the bolt 13, and hence it is made long enough to pass through a slot 24 in the escutcheon plate 12, its outer end being fitted with a knob 25.

90 On the sleeve 19 is fixed a peripherally toothed ring 26, and on the sleeve 17 is fixed a similar ring 27. The ring 26 carries a dial ring 28, and ring 27 carries a dial ring 29. The tumblers 18 and 20 are set 95 by rotating the rings 28 and 29, and the combination can be readily changed by changing the position of the dial rings on the toothed rings 26 and 27, the dial rings being removable for this purpose. It will 100 be understood, of course, that the dial rings are fast on the toothed rings, and as the latter are fast on the sleeves carrying the tumblers, said tumblers are operated by turning the dial rings. The peripheries of 105 the dial rings are beveled so that when they are assembled they form a cone at the apex of which the knob or head 25 is located. The peripheries of the dial rings are also graduated as is usual in permutation locks, 110

and they are located on the outside of the plate 12, the ring 28 seating at its base against the outer face of said plate and covering the slot 24 therein.

5 The operating means of the tumblers 18 and 20 are on the outside of the door, and on the inside of the door is a means for permitting operation of the bolt 13 as a night latch. For this purpose, the rear face of 10 the bolt 13 has a recess 29 in which seats a rotatable tumbler 30 having the shape of a disk which is provided with a peripheral notch 31. On the rear face of the block 15 is a lug 32 which is so dimensioned that when 15 the notch is in alinement therewith it can pass thereinto.

The tumbler 30 is operated by a knob 33 carried by a stem 34 extending from the center of the tumbler, the knob being located 20 outside the door 10. In this side of the door is a slot 35 running in the direction of the length of the bolt 13 and registering with a slot 36 in the back wall of the lock casing 11. In the slots 35 and 36 is 25 mounted a slide block 37 through which the tumbler stem 34 passes and in which it is rotatable. The end of the block 37 which is next to the tumbler 30 has a disk-like head or enlargement 38, and a recess 39, 30 which latter houses a spring 40 coiled around the stem 34 and bearing against the face of the tumbler, the purpose of this spring being to make the tumbler work tightly and not turn too freely. The end of the slide block 37 which is next to the base of the knob 33 has an outstanding pin 41 which extends into a recess 42 to enter a selected one 35 of a pair of keeper apertures 43. The tumbler 30 is operable by the knob 33, and when 40 the pin 41 seats in one of the apertures 43 the tumbler notch 31 is in alinement with the lug 32, whereas when the pin seats in the other aperture, the tumbler notch is out of alinement with the lug. The block 39 is 45 free to yield in the direction of the length of the stem 34 sufficiently to permit the pin 41 to snap into the apertures 43. The block 39 is of course non-rotatable so that the knob 33 may be operated as described. It will be 50 evident from the foregoing that the tumbler 30 can be readily set without applying graduations or other indicia to the knob 33.

To the bolt 13 is also connected a spring 44 tending to advance the same to locking 55 position.

When the bolt 13 has been advanced to locking position by the spring 44, it is locked in this position by placing the tumblers 18 and 20 across-wise of the slot 23, as shown 60 in Fig. 3. The bolt now cannot be slid rearward or retracted as this movement is blocked by the tumblers and the stationary plate 21 in the opening 22 of which the tumblers seat. The bolt cannot be retracted from 65 the outside of the door until the tumblers

are set to pass through the slot 23. When this is done, and the knob 25 and the parts associated therewith are pushed rearwardly so that the block 15 pressing against the rear end of the bolt slot 14 forces the bolt 70 rearwardly and thus retracts the same. When the bolt 13 is advanced and locked by the tumblers 18 and 20, it can be retracted from the inside of the room by operating the knob 33 to place the notch 31 of tumbler 30 75 into alinement with the lug 32 of the block 15. The knob 33 can now be moved inwardly in the direction of the length of the bolt, whereupon the latter is carried along with the tumbler 30 and retracted. The tumbler 80 can pass rearwardly as it is now not blocked by the lug 32, the notch 31 having been set to register with the lug, so that when the tumbler is slid back as described the notch goes over the lug. To lock the bolt in advanced 85 position from the inside of the room it is necessary only to turn the tumbler 30 so that its notch 31 is out of registry with the lug 32, the tumblers 18 and 20 of course being also set in bolt-locking position as before. 90 When the tumblers 18 and 20 are set to permit the retraction of the bolt, the latter can be retracted by the knob 33 without any setting of the tumbler 30.

I claim:

1. A permutation lock comprising a casing, a slidable bolt in the casing and having a longitudinal slot, a block in the slot on which the bolt is slidable, a bolt-retracting stem carried by the block, telescopically connected sleeves rotatably mounted on the stem, rotatable tumblers carried by the sleeves, a stationary plate having an opening in which the tumblers work and an exit slot for the tumblers leading from said opening, 100 dial rings adjustably mounted on the sleeves, and a knob on the outer end of the stem, said knob and dial rings being concentrically arranged.

2. A permutation lock comprising a casing, a slidable bolt in the casing and having a longitudinal slot, a block in the slot on which the bolt is slidable, a bolt-retracting stem carried by the block, rotatable tumblers carried by the stem and consisting of cross 110 bars having one end wider than the other, and a stationary plate having an opening in which the tumblers seat and an exit slot for the tumblers leading from said opening, the width of said slot corresponding to the narrow ends of the tumblers.

3. A permutation lock comprising a casing, a slidable bolt in the casing and having a longitudinal slot, a block in the slot on which the bolt is slidable, a bolt-retracting stem 125 carried by the block, and extending from one side of the bolt, a rotatable tumbler carried by the other side of the bolt, said tumbler having an edge recess, an actuator for said tumbler, said actuator being also slidable 130

- for retracting the bolt, an abutment on the aforesaid block positioned to intercept the tumbler and to seat in the tumbler recess when the latter is in alinement therewith,
5 rotatable tumblers carried by the bolt-retracting stem, and a stationary plate having an opening in which the last-mentioned tumblers work and an exit slot for said tumblers leading from the opening.
- 10 4. A permutation lock comprising a casing, a slidable bolt in the casing and having a longitudinal slot, a block in the slot on which the bolt is slidable, a bolt-retracting stem carried by the block, and extending
15 from one side of the bolt, a rotatable tumbler carried by the other side of the bolt, said tumbler having an edge recess, a stem extending from the tumbler, a slide block through which said stem rotatably passes, a
20 knob on the outer end of the stem, cooperating means on the knob and the slide block for indicating the position of the tumbler, an abutment on the first-mentioned block positioned to intercept the tumbler and to seat in the tumbler recess when the latter is in alinement therewith, rotatable tumblers carried by the bolt-retracting stem, and a
25 stationary plate having an opening in which
- the last-mentioned tumblers work and an exit slot for said tumblers leading from the opening.
5. A permutation lock comprising a casing, a slidable bolt in the casing and having a longitudinal slot, a block in the slot on which the bolt is slidable, a bolt-retracting 35 stem carried by the block, and extending from one side of the bolt, a rotatable tumbler carried by the other side of the bolt, said tumbler having an edge recess, a stem extending from the tumbler, a slide block 40 through which said stem rotatably passes, a knob on the outer end of the stem, a pin carried by the slide block, keeper recesses in the knob for the pin, said recesses being located to indicate different positions of the 45 tumblers, an abutment on the first-mentioned block positioned to intercept the tumbler and to seat in the tumbler recess when the latter is in alinement therewith, rotatable tumblers carried by the bolt-retracting stem, and a 50 stationary plate having an opening in which the last-mentioned tumblers work and an exit slot for said tumblers leading from the opening.

In testimony whereof I affix my signature. 55
LOUIS P. DAGES.
